UNITED STATES PATENT OFFICE.

WILLIAM H. MINER, OF CHAZY, NEW YORK.

DRAFT-GEAR FOR RAILWAY-CARS.

1,357,888.

Specification of Letters Patent. Patented Nov. 2, 1920.

Application filed March 21, 1917, Serial No. 156,475. Renewed August 30, 1920. Serial No. 407,061.

To all whom it may concern:

Be it known that I, WILLIAM H. MINER, a citizen of the United States, residing at Chazy, in the county of Clinton and State 5 of New York, have invented a certain new and useful Improvement in Draft-Gears for Railway-Cars, of which the following is a full, clear, concise, and exact description, reference being had to the accompanying 10 drawings, forming a part of this specification.

My invention relates to improvements in draft gears for railway cars.

One of the objects of my invention is to 15 provide a simple and efficient, direct acting, compound, differential, tandem spring and friction draft gear. Other objects will appear from the description of my invention herein following.

20 In the drawings forming a part of this specification, Figure 1 is a side elevation, partly in vertical longitudinal section, of a draft gear embodying my invention. Fig. 2 is a horizontal section taken on line 2—2 of 25 Fig. 1. In Figs. 1 and 2 the draft gear is shown in its normal position. Fig. 3 is a horizontal section showing the position of the parts when in full buff. Fig. 4 is a cross section taken on line 4—4 of Fig. 1. Fig. 5 30 is a perspective view of one of the friction wedges. Fig. 6 is a perspective view of one of the friction shoes.

Referring to the drawings, the numerals 10—10 indicate draft sills or members of the car frame to which the draft rigging is applied. Mounted upon the inner faces of these sills, and secured thereto preferably by the rivets 11—11, are the stop members 12, providing the front stop shoulders 13—13 against which the front follower 14 is arranged to engage, and with the rear stop shoulders 15—15 against which the rear follower 16 is adapted to engage. They are also provided with front and rear intermediate stop shoulders 17 and 18, respectively, between which the friction shell 19 is mounted. The friction shell 19 may externally be of any suitable shape; the particular form illustrated in the drawings being provided with the front and rear wings 20 and 21, respectively, the same being employed in conjunction with the intermediate stop shoulders to maintain the shell in a stationary position between the draft members of the car. The shell 19 has a hollow interior 20 that may be of any suitable cross

section, that illustrated in the drawings being rectangular and is provided with friction faces which, for convenience, we denominate the front internal friction face 22 and the rear internal friction face 23. Friction elements 24 are mounted within the shell, the same being arranged in front and rear sets 25 and 26, respectively. Each set of friction elements comprises a wedge and 60 shoes, the front wedge being indicated at 27, and the rear wedge at 28. The friction shoes of the front set are shown at 29—29, and those of the rear set at 30—30. Both of 65 said friction faces 22 and 23 internally provided in the shell are tapered from their outer ends toward the center of the shell. In the form of my invention illustrated in the drawings the front internal friction face 22 is slightly tapered, as clearly shown in 70 Figs. 2 and 3, and the rear internal friction face 23 is tapered slightly more than is the front friction face, as is also illustrated in the said figures of the drawings. Each of the wedges 27 and 28 is provided with the 75 wedging faces 31—31 which are in wedging engagement with the wedging faces 32—32 provided, respectively, upon the adjacent friction shoes. Each friction shoe has an 80 external friction face 33 which engages the 85 adjacent internal friction face of the shell. The front wedge 27 is provided with a stem 34 which in normal position of the parts is spaced away from the boss 35 upon the front 90 follower 14. The springs 36 are mounted between the front wedge 27 and the front follower 14, and in their normal position maintain the space, as indicated at the numeral 37 in Fig. 2 of the drawings, between the boss 35 and the wedge stem 34. The rear 95 wedge 28 is provided with a stem 38 which in normal position of the gear is spaced apart from the boss 39 with which the rear follower 16 is provided. The space, as indicated by the numeral 40 in Fig. 2 of the 100 drawings, between the said boss 39 and the rear wedge stem 38 is slightly greater than the space between the front wedge stem 34 and the boss 35. Mounted between the rear follower 16 and the rear wedge 28 are the 105 rear springs 42.

In describing the friction shoes as arranged in a front set 29 and rear set 30, I do not intend to convey the impression that the said sets are of necessity separate, as opposed shoes of the front and rear sets may be made integral, if so desired.

The friction shell 19 is held against downward displacement by the carry-plate 43 which is detachably secured to the draft members by suitable means, as, for instance, 5 the bolts 44—44.

A yoke 45 surrounds the draft gear structure and provides an operative connection between it and the draw-bar 46, to which it is appropriately secured, as, for instance, 10 by the rivets 47.

It will be observed that the draft gear may be easily mounted between, or dismounted from the sills, as the removable 15 carry-plate supports the entire structure, including the yoke, the yoke in turn supporting the followers.

In order to further explain my invention, I will now describe its operation first in 20 resisting shocks occasioned by the rearward movement of the draw-bar, or buffing movement, as it is commonly called. On such movement the front follower 14 is forced rearwardly against the resistance of the front springs 36, which are held at their rear 25 by the friction elements, and the rear spring 42, which is seated against the rear follower 16, said rear follower being held by the rear stop shoulders 15—15. Before the friction elements exert their full resisting action, the 30 boss 35 upon the front follower 14 will engage the stem 34 with which the front wedge is provided, thus forming a solid column from the draw-bar to the front wedge 27, which moves rearwardly, spreading the friction 35 shoes 29 and forcing them into frictional engagement with the front internal friction face 22 of the friction shell 19. The front wedge 27 in the illustration of my invention shown in the drawing is more acute 40 than is the rear wedge 28.

In actual practice, the front friction shell surfaces are tapered or relatively converged less than the rear shell friction surfaces. Furthermore, the normal space left between 45 the wedge stem 34 and the boss 35 is preferably less than the space left between the rear wedge stem 38 and the boss 39 so as to give a longer preliminary spring action under draft than in buff.

50 In operation, assuming an inward or buffing movement of the drawbar, the first action will be the preliminary spring action until the boss 35 engages the stem 34. Thereafter, inward movement will be communicated to the wedge 27 and shoes 29 which will be resisted by the rear spring 55 acting through the wedge 28 and shoes 30. In a draft or outward movement of the

drawbar, the first resistance will be that of the rear spring until the boss 39 engages 60 the rear stem 38. Thereafter forward movement will be communicated to the wedge 38 and shoes 30 which will be resisted by the front spring acting through the wedge 27 and shoes 29. By varying the taper of the 65 front and rear sets of friction surfaces and by changing the wedge angles, different capacities may be obtained as will be understood by those skilled in the art.

It will be observed that my invention provides a strong spring resistance through the tandem arranged springs, and that a compound differential action is obtained in the friction shell through the arrangement of a blunter wedge at one end of the friction elements and a more acute wedge at the other end of the friction elements, and also through providing the friction shell with an internal friction face of a certain taper at one end, and of a different taper at the other 80 end.

A connecting bolt 50 passes through the wedges and at its ends is counter-sunk in the wedge stems 34 and 38, respectively, allowance being made for sufficient play there- 85 in when the wedges approach each other.

I claim:

In a railway draft rigging, the combination with draft sills, front and rear stop-acting means, and front and rear followers 90 coöperable with said means, of a double ended friction shell located between said followers and stationary with respect to said sills, one end of said shell having friction surfaces arranged at one angle to the axis 95 of the shell and the other end of the shell having friction surfaces arranged at a different angle to said axis, both sets of friction surfaces being inclined inwardly from the outer ends of the shell toward its center so that the interior of the shell has its minimum dimension intermediate the ends thereof, a set of friction elements coöperable with the friction surfaces at one end of said shell, another set of friction elements 100 coöperable with the friction surfaces of the other end of said shell, and spring means interposed between each follower and the nearest set of friction elements, all of said friction elements moving relatively to the 110 friction shell in both buff and draft.

In witness that I claim the foregoing I have hereunto subscribed my name this 19th day of Mar., 1917.

WILLIAM H. MINER.
